UNITED STATES PATENT OFFICE.

WALTER W. LANGDON, OF CINCINNATI, OHIO.

DEVICE FOR SOLDERING ICE CANS AND THE LIKE.

Application filed December 26, 1921. Serial No. 524,813.

To all whom it may concern:

Be it known that I, WALTER W. LANGDON, a citizen of the United States, residing at Cincinnati, in the county of Hamilton and 5 State of Ohio, have invented certain new and useful Improvements in Devices for Soldering Ice Cans and the like, of which the following is a specification.

My invention relates to means for soldering ice-cans and other similar structures composed of galvanized metal or tin.

Ice-cans are expensive to make and only last a comparatively short time before they commence to rust at their joints around the 15 lower edge or end of the can. Heretofore, after the cans have rusted in the seams or joints it has been difficult to resolder them.

The object of my invention is to provide simple, efficient, convenient and economical 20 means for resoldering such ice-cans or other structures needing repair.

My invention consists in the construction, combination and arrangement of parts as herein set forth and claimed. My invention 25 also consists in the method employed.

In the drawings:

Fig. 1 is a side elevation showing the means for suspending an ice-can in operative relation with a solder receptacle mounted 30 upon a suitable furnace;

Fig. 2 is a side elevation partly broken away of a furnace with solder container mounted thereon and showing the furnace door in open position;

Fig. 3 is a perspective view of the upper 35 end of an ice-can;

Fig. 4 is a perspective view of the lower end thereof;

Fig. 5 is a perspective view of the solder 40 container;

Fig. 6 is a section on the line 6—6 of Fig. 1; and

Fig. 7 is an enlarged edge view of rope, 45 pulley and ratchet wheel.

In the embodiment of my invention as 50 illustrated I provide a frame suitably mounted having a pair of arms 1 each having an inturned ear 2 with a vertical hole 3 therethrough to receive and guide the upper ends of sliding rods 4, respectively.

A cable 5 having hooks 7 is attached at its upper end to eye 8 suitably mounted in an elevated position. The inner ends of 55 said cable are attached to a pair of centrally disposed interposed collars 6 connect-

ed by rigid coupling 9 and each collar is provided with a vertical hole 10 therethrough in alinement with holes 3, respectively, to receive and support sliding rods 4. Each sliding rod 4 is provided on its lower end with knuckle 12 to which tongs 13 are pivotally connected, said tongs also having a transverse pivotal connection at 11 thus permitting said tongs to move on said respective pivots in two directions either toward or from each other or each laterally in the same direction to permit the hooks 14 to engage or disengage flanges 15 of ice-can 16.

Cable 5 passes over pulley 17 journaled 70 at 19 to hanger 18 suitably mounted in an elevated position, thence over groove 33 of pulley 20 journaled at 21 to hanger 22. Rigidly connected to pulley 20 is a ratchet wheel 23 engaging pulley 24 in alinement therewith.

Open solder container 25 is removably secured in the open top of furnace 26 with its side flanges 32 resting upon and supported by side flanges 30 of furnace 26. Door 31 80 permits access to valve 27 which controls the fuel from supply pipe 28 to burner 29 by which the solder in container 25 is melted and maintained in liquid form.

When it is desired to solder the lower end 85 such as 34 of ice-can 16 by means of my invention dip the lower end of the ice-can into the hot liquid solder, then pour into the ice-can a quantity of muriatic acid which will penetrate the joint and eat away the 90 rust. This requires only about one-half minute. Then remove the ice-can for about a minute to permit the acid to completely eat away the rust. Then dip the joint to be soldered into the liquid solder for an instant, 95 then draw it out, when the solder will cool and set. Each lower edge of the can is treated in the same way and this treatment renders the can substantially as good as new at a comparatively small expense.

In order to suspend the ice-can in proper position to be soldered the hooks 14 are caused to engage flanges 15 of the can. It is then hoisted by means of pulleys 20 and 105 17 to the proper height to be inserted into the container. By a reverse movement of pulley 20 the tension of rope 5 is relaxed and its descending movement will cause bottom 34 on its inner and outer surfaces to engage the liquid solder in container 25. A reverse 110

movement of pulley 20 will withdraw end 34 from the liquid solder and hoist the can to its initial position.

What I claim as new and desire to secure 5 by Letters Patent is:

1. In a device for soldering ice-cans, a solder container, a pair of spaced apart arms each having an inturned ear provided with a vertical hole, a sliding rod mounted in 10 each of said holes and guided thereby, a flexible member adapted to support said sliding rods, means for raising and lowering said sliding rods and tongs pivotally attached to said rods to detachably support an ice-can, 15 for the purposes set forth.
2. In a device for soldering ice-cans, a pair of upright arms each having an ear provided with a vertical hole, sliding rods

having their upper ends guided in said holes, respectively, a collar mounted on each sliding rod, a coupling connecting said collars, a flexible cable attached to said collars, a hook and eye adapted to support one end of said cable in elevated position, tongs pivotally attached to the lower end of said sliding rods and having movement horizontally in transverse directions, and means for raising and lowering said tongs. 20

3. In a device for soldering ice-cans, a liquid solder container, flexible supporting means, guiding means, pivotally mounted tongs adapted to swing toward each other to support an ice-can and means for lowering the same into said solder container and raising it therefrom, as specified. 25

WALTER W. LANGDON.
